CLAIM

The ornamental design for a kayak roller with suction cup, as shown and described.

DESCRIPTION

FIG. 1 is a front perspective view of a kayak roller with suction cup, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view show in the kayak roller with suction cup in another state of use.

The broken lines in the drawings illustrate the portions of the kayak roller with suction cup, which form no part of the claimed design.
